UNITED STATES PATENT OFFICE.

JOSEPH K. BLUM, OF NEW YORK, N. Y.

HAMMER FOR PULVERIZERS.

1,366,512.

Specification of Letters Patent. Patented Jan. 25, 1921.

Application filed December 14, 1918. Serial No. 266,677.

To all whom it may concern:

Be it known that I, JOSEPH K. BLUM, a citizen of the United States, and a resident of the city, county, and State of New York, 5 have invented certain new and useful Improvements in Hammers for Pulverizers, of which the following is a specification.

My invention relates to an improvement in hammers for pulverizing machines, and 10 can be applied to any rotary hammer pulverizing machine. My invention, moreover, may be embodied in hammers of the bar or radial spoke types, such as are shown in Patents Numbers 1,185,619, and 1,125,187 15 respectively.

I have found in operating all forms of rotary hammer mills that the hammers or portions of the hammers adjacent the casing wear faster than the hammers or portions 20 of the hammers toward the center of the hammer space. My observations have led me to believe that this uneven wear is caused by the action of the hammers in forcing their way through the loose material. 25 This action appears similar to that which occurs when forcing a stick through a group of loose stones. The tendency is for the stones to move out of the path of the stick in a direction at right angles to the line of movement 30 of the stick. In a similar way, the stones or material in a crusher crowd toward the casing in a direction longitudinally of the shaft. Thus the material crowds in between the end portions of the hammer structure 35 and the casing, wearing off the end portions of the hammer structure. As this wear increases the distance between the ends of the hammer structure and the casing, the space for material, increases, and 40 the rate of wear accelerates as it goes on. Consequently, the space between the ends of the hammer structure and the casing increases with undesirable rapidity to the point where the mechanical efficiency is reduced to the point that the renewal of the 45 hammer structure is necessitated. Moreover, the hammers or hammer portions adjacent the flat sides or heads of the casing thus are forced to operate on a larger body 50 of material with consequent greater wear on their outer faces than is the case with those near the center of the hammer space. The results of such uneven radial wear are also highly disadvantageous. It is essential for

good performance that the clearance between 55 the breaking members and the revolving hammers be uniform, but the uneven wear just mentioned prevents this condition from being maintained. Moreover, for mechanical reasons, the results of uneven wear can- 60 not to be corrected simply by radial adjustment of the hammers, although it is essential to the satisfactory operation of the machines that this adjustment be made. In consequence of this, an entire set of hammers 65 of a given machine had often, prior to my invention, to be discarded while the major portion of the active surface was still suitable for use, although a set of new hammers involves a material expense. 70

It is accordingly the principal object of my invention to so design the hammer structure of a rotary pulverizer as to prevent as far as possible the accumulation of an excess of material being operated on near the 75 ends of the hammer structure.

A further object of my invention is to provide hammer structures for rotary pulverizers in which the radial wear shall be approximately uniform in the direction 80 parallel to the shaft.

A final object of my invention is to provide hammer structures for rotary pulverizers which shall prevent undue wear on the end portions of the said structures. 85

In carrying out the objects just mentioned in accordance with my invention, I have constructed the hammers so that the faces of the hammers which look forward in the direction of rotation shall be further advanced 90 in the direction of rotation near their ends than toward the center. Points on the radial faces of the hammers which strike the material thus outline a concaved surface and thus tend to force the material toward the 95 center of the shaft, balancing the opposite tendency which otherwise would crowd the material toward the flat sides or heads of the casing.

In the drawing accompanying and forming 100 a part of this disclosure, I have illustrated several of the possible arrangements of hammers embodying my invention.

In the drawing, Figure 1 is a partial view partly in sec- 105 tion and partly in elevation, of a machine of the bar-hammer type having my invention embodied therein.

Fig. 2 is a detail view of one of the hammers shown in Fig. 1 looking in a direction radially toward the shaft of the machine.

Fig. 3 is a partial view in elevation of a machine of the radial hammer type also having my invention embodied therein.

Fig. 4 is a detail of a row of radial hammers such as shown in Fig. 3, when viewed looking radially toward the shaft.

Fig. 5 is a detail view looking in a radial direction of a hammer structure embodying my invention, this form being of the same general type as that shown in Figs. 1 and 2, but having differently formed radial faces.

Fig. 6 is a detail view looking in a radial direction of a hammer structure of the radial hammer type, having my invention embodied therein, illustrating the application 20 of the invention in cases where the individual hammers are of rectangular cross-section; of progressively lessening circumferential dimension in passing from the ends of the structure toward the center.

Fig. 7 is a detail view looking in a radial direction of a hammer structure of the radial hammer type having my invention embodied therein, illustrating the application of the invention in cases where the individual hammers are all rectangular and of the same cross-section.

In the separate views the same part is designated by the same reference character.

Referring to the drawing in detail, 1 is the shaft of a pulverizing machine of the rotary hammer type provided with a casing having flat heads or ends 2. Mounted to rotate with the shaft 1 within the heads 2 is a series of disks, such as 3. Hammers, such as 7, of the bar type are pivotally mounted in said disks by means of hollow hubs such as 4, surrounding cylindrical bearing members such as 5, mounted in the disks 3 by means of pins such as 6. The pins 6 are eccentric to the members 5 to permit adjusting the hammers 7 radially of the casing. The mechanical details heretofore described herein are given simply for purposes of convenience, said details forming no part of my present invention and being disclosed in said Patent No. 1,185,619. As clearly shown in Figs. 1 and 2, the radial active faces 8 of the hammers 7, which strike the material, project forward farther in the direction of rotation at the ends 9 that at the center, the face 8 being slightly concave. The material consequently is urged toward the center of the hammers sufficiently to counteract its normal tendency to move in the opposite direction.

Referring more particularly to Fig. 5, it will be seen that the hammer structure 7^a illustrated therein has radial faces of stepped formation presenting shoulders such as 14 which run in the radial direction on the ac-

tive face of the hammer. The faces of the individual steps are, however, flat in the axial direction, as appears in the figure. It will be seen that the circumferential dimension of this type of hammer decreases in 70 passing from the ends of the hammer to the center, thus tending to draw the material away from the ends in the same manner as the form shown in Fig. 2, since material rebounding from a corner tends to fly toward 75 the center.

In Figs. 3 and 4, I have shown my invention as applied to the hammer of a machine such as shown in Patent 1,125,137. In such machines, the hammers, such as 10, are of 80 radial or spoke form and are pivoted in rows to pins or bolts such as 11, suitably mounted parallel to the rotary shaft 12. In this type of machine there is a space, such as 13, intermediate each pair of hammers 10 in a 85 given row approximately of the same dimension parallel to the shaft as the individual hammers. However, the same tendency of the material to accumulate at the ends of the rows is present in this type of machine also, and the results are similar to those in the type first discussed. I find that this difficulty can be overcome in case of the radial type hammer by arrangements broadly similar to those previously described for the U-type hammer. As clearly shown in Figs. 3 and 4, the active faces of the individual hammers of each longitudinal row of radial or spoke hammers can be shaped so that they form sections of a concave surface, the portions of the radial active faces of the hammers nearest the casing projecting farther forward in the direction of rotation than the portions nearest the center of the row. In other words, if the 90 hammers were arranged in juxtaposition in the row, without appreciable spaces between, the radial active surface would be substantially the same when viewed in the direction looking radially toward the shaft as in the 95 form shown in Figs. 1 and 2.

Referring more particularly to Fig. 6, this figure illustrates a hammer structure composed of hammers such as 10^a of the radial spoke type, each of which is of rectangular cross-section. In order to obtain the effect of drawing the material away from the ends of the structure, the individual hammers are of successively decreasing circumferential dimension in passing 105 from the ends to the center of the structure, so that the material rebounding from the outside corner of a hammer is partially cut off by the hammer to the outside of the point of rebound, while material rebounding from 110 the inside corner of a hammer is free to travel toward the center. The active faces of the hammers 10^a are flat in the axial direction as shown in the figure.

In the forms shown in Figs. 1 and 2, Figs. 130

3 and 4, Fig. 5 and Fig. 6, the hammer structures are made symmetrical with respect to a radial plane through the shaft of the machine, so that they may be reversed in operation, but this is not necessarily the case as shown in Fig. 7.

The hammer structure shown in Fig. 7 operates on the material in the same manner as the form shown in Fig. 6, but it will be obvious that the hammer structure of Fig. 6 will operate equally well when revolving in either direction, whereas the structure shown in Fig. 7 projects farther in the circumferential direction at the center than at the ends on one side of the structure. This is owing to the fact that the individual hammers such as 10^b are of the same cross-section along the entire length of the structure, the recess in the center of one face or side of the structure being produced simply by angular adjustment of the individual hammers 10^b with respect to their axis. In this form of the invention, also, the active faces of the hammers are shown as straight 25 or flat in the axial direction.

In a hammer structure according to my invention, there will be a space between a straight edge laid along the radial face of the structure parallel to the shaft and the radial active surface near the center thereof. The amount of this distance, which is the measure of concavity, depends upon the hardness and elasticity of the material and may be as small as $\frac{1}{4}$ of an inch for a hammer structure twelve inches along the shaft if intended for use in pulverizing soft materials. I prefer that the radial active face of a hammer structure embodying my invention should, when viewed radially of the

shaft, outline a parabola, since this form of 40 surface gives the most advantageous rebound.

It will be seen that all the forms of hammer structure according to my invention, as shown in the drawing, are substantially 45 symmetrical with respect to the central transverse plane thereof. While not essential, this is the preferred arrangement.

Having thus described my invention, I claim:

1. A hammer structure for rotary hammer pulverizing machines, extending longitudinally of the axes of rotation and having radial active areas on opposite faces thereof, said radial active areas projecting farther 55 forward in the direction of rotation at the ends than at the center of the structure.

2. A hammer structure for rotary pulverizing machines, in which the thickness of the hammer body between two adjacent radial surfaces is less at the radius through 60 the center of the axis of rotation than at the ends of the structure.

3. A hammer structure for rotary hammer pulverizing machines, the radial active 65 surfaces of which when viewed radially of the axis of rotation of the structure, have points defining a parabolic curve the ends of which extend forward in the direction of rotation as compared to the center. 70

4. A pulverizing machine comprising, in combination, a casing and a swinging rotary hammer structure therein, the active faces of said structure projecting farther forward in the direction of rotation at the points 75 nearest said casing than at the center.

JOS. K. BLUM
